UNITED STATES PATENT OFFICE.

WILLIAM B. MASON, OF BOSTON, MASSACHUSETTS, ASSIGNOR TO THE
MASON REGULATOR COMPANY, OF SAME PLACE.

PRESSURE-REGULATOR.

SPECIFICATION forming part of Letters Patent No. 617,938, dated January 17, 1899.

Application filed July 10, 1897. Serial No. 644,059. (No model.)

To all whom it may concern:

Be it known that I, WILLIAM B. MASON, a citizen of the United States, residing at Boston, in the county of Suffolk and State of Massachusetts, have invented certain new and useful Improvements in Pressure-Regulators, of which the following is a specification, reference being had therein to the accompanying drawings.

10 My invention consists in a novel and improved construction of reducing-valve mechanism.

The invention is fully set forth in the following description, and the novel features thereof are pointed out and clearly defined in the claims at the end of this specification.

15 The accompanying drawings illustrate the best embodiment of the invention which I have yet contrived, in which—

20 Figure 1 is a view in side elevation of the said embodiment. Fig. 2 is a view thereof in central vertical section, some of the parts being shown in elevation for greater clearness. Fig. 3 is a view in vertical section on a plane 25 at right angles to that of Fig. 2, showing the balance-valve and valve-body, as also the valve-operating stem. Fig. 4 is a view, on an enlarged scale, of a portion of Fig. 2.

I will refer in the following description to 30 the reduction of steam-pressure, although, as will be obvious, the devices hereinafter explained may be employed for the reduction of the pressure of other fluids, and I do not desire to limit myself to its use in the reduction of steam-pressure.

35 Having reference to the drawings, 1 is the body or casing of a balanced valve, which body is provided at 22 with flanged connections, by means of which it may be inserted 40 in a line of pipe in the usual manner.

3 is the inlet-passage, and 4 the outlet-passage, of the balanced valve.

5 is the valve proper or slide, which is arranged to slide vertically within a housing or 45 valve-seat in well-known manner.

6 is a valve-stem, which passes through a suitable stuffing-box 7 in the top 8 of the valve-body. The upper end 9 of the stem is fitted to slide vertically in a bearing that is formed 50 in the upper end 10 of the upwardly-extending curved arm 11, which latter is secured to

or formed integral with the top 8 of the valve-body. The part 10 is slotted vertically at 12, and a slot 13 is formed through the upper end 9 of the valve-stem. A lever 14, carrying a weight 14, passes through the slots 12 and 13 and is pivoted at one end at 15, at the bottom or rear end of the slot 12, in the arm 11. (See Fig. 2.) The other end of the lever 14 is pivoted at 16 to a connecting-rod 17, the opposite end of said connecting-rod 17 being pivoted to the upper end of a piston-rod 18, to which the piston 19 is secured. The piston 19 slides in a cylinder 20, its rod 18 being fitted to an opening in the head 21 of the said cylinder. It will be obvious that the vertical movement of the piston 19 will cause the movable part or slide of the balanced valve 5 to be moved, and thus opened or closed. The mechanism by means of which the said piston 19 is caused to move as the pressure varies on the low side of the valve, which pressure it is desired to regulate, is as follows: A is a sediment-chamber, which is flanged at the upper end, so that it may be 65 securely bolted, as shown at 22, to the under side of the valve-body 1, said body being provided with flanges 23 for that purpose. The lower end of the sediment-chamber is provided with a blow-off cock, as shown at 24. The chamber A is supplied by means of a pipe 25 with water under pressure, the pipe 25 connecting with any suitable source of water-supply. The outlet-pipe 26 enters the sediment-chamber A near the upper end thereof, so that 70 any sediment in the water may be allowed to settle and may be drawn off or cleaned out through the blow-off cock 24. The said outlet-pipe 26, leading from the sediment-chamber, connects with the water-inlet 27 of the valve 28. The casing or body of the said valve 28 is provided with a projecting portion 29, extending at right angles to the body proper of the said valve, and provided at its end with flanges, by means of which it is securely 75 bolted at 30 to the cylinder 20. A plunger 31 is adapted to move vertically through an opening in the top or cap 32 of the body of the said valve 28, and the lower end of this plunger is provided with a valve-stem 33, which moves in a vertical opening in the valve-body, said valve-stem having enlargements 80

at 34 and 35, which fit the said vertical opening or passage. At the lower end of the valve-body 28 I provide a drip-opening 36. A passage 37 leads from the water-inlet 27 to the 5 vertical valve-passage, and from a lower point of the said valve-passage an opening or passage 38 leads through the projecting portion 29 to the cylinder-body, and thence down in the cylinder-body to a point near the lower 10 end thereof, and thence into the cylinder above the lower head 39 thereof. The water-valve 28 may be termed a "two-way" valve. When the valve-stem is raised, the water-supply is cut off and the water under the piston 19 and in the passage 38 is allowed to 15 escape through the drip-opening 36, thus removing pressure from the under side of the piston and permitting the piston to descend under the load of the weight 141 on the lever 14. When the valve-stem is lowered, the drip 20 is closed and the water is permitted to pass from the water-inlet through the passage 38 and under the piston 19, thereby causing the piston to move upwardly, thereby lifting the weight 141 and the lever 14. As will be clear, 25 when the lever 14 is raised the valve 5 will be opened and a larger amount of steam or other fluid will be permitted to pass therethrough, and when the lever 14 is lowered the movement of the said valve is reversed and the valve is gradually closed. It will be clear, 30 therefore, that the opening or closing of the water-valve 28 will effect the opening or closing of the valve 5.

For the purpose of controlling the movement of the water-valve 28 and effecting the opening or closing of the valve 5 in accordance with the variation of pressure on the low-pressure side of the said valve I provide 35 a cylindrical frame or base B, which is supported upon a bracket-arm C, that is secured to or integral with the sediment-chamber A. The cylinder 20 is provided with a base 45 and is mounted upon the cylindrical base or 40 support B and secured thereon by means of bolts 46. Within the base or support B and near the base thereof I secure a diaphragm 50, which may be of rubber or other suitable material, and which is provided on top with 45 a cylindrical disk or cover 52, which last is raised in the center, as shown at 53, and provided with a hardened bolt or pin 54, that is set in an opening in the disk 52, formed to receive said pin 54. The top of the pin is wedge-shaped, forming a knife-edge, upon which rests a hardened block 57, that is provided 50 upon the weighted lever D. A second hardened block 58 on the said lever D rests against the wedge-shaped end of a screw 59, the latter being applied to the base or support B and serving as the fulcrum for the lever D. 55

60 is a link connecting the lever D with the floating lever 61, the latter having pivotally connected to one arm thereof the plunger 31. The other arm of the said floating lever is 60 loosely connected by a pin 62 with an obliquely moving slide 63, the latter having its

elevated outer extremity furnished with a horizontal slot 64, which receives the said pin. The said slide 63 is fitted to an inclined 70 hole in the head 21 of cylinder 20, and the lower end of the said slide fits within a groove 65, that is formed in the side of the piston-rod 18. The said groove varies in its depth, the said depth increasing gradually from the lower end thereof to the upper end thereof. The bottom of the groove therefore acts as a longitudinally-extending cam as the piston-rod 18 rises and falls, it operating to occasion 75 endwise movement of the slide 63. As the piston-rod is raised the said cam acts to force the slide 63 outwardly, raising the fulcrum end of the floating lever, while as the piston-rod is lowered the said cam permits the slide to move inwardly, thereby lowering the fulcrum end of the floating lever. As will be 80 understood, this action of the cam upon the fulcrum-slide 63 follows after movement has been communicated to the floating lever and to the valve-stem 33 of valve 28 from the lever 85 D of the pressure-measuring devices, and it operates to bring the said valve-stem 33 of the valve 28 back into the position which closes the passage 38 against either the entrance of water or the escape thereof after 90 movement of the piston 19 in the required direction has taken place to the extent which is necessary in order to occasion the movement of valve 5, which will restore the predetermined pressure on the lower side of the 95 said valve.

The general operation of the described devices will be obvious to those who are skilled in the art. Communication is established in usual manner between the line of pipe on the 100 low-pressure side of valve 5 and the pressure-measuring devices, as by means of piping (not necessary to be shown) joined to the pipe 71. The said pipe 71 (see more particularly Fig. 4) communicates with passage-ways 105 leading to the space beneath diaphragm 50, so that the pressure on the low-pressure side of valve 5 is permitted to make itself felt at diaphragm 50. When such pressure rises above the predetermined point, it forces upward the 110 diaphragm 50 and weighted lever D, thereby through the link 60 turning the floating lever 61 about the pivotal connection of the latter at 62 with slide 63. This raises the plunger 31 and valve-stem 33, so as to cut off within 115 the valve 28 the liquid-pressure acting beneath piston 19, and at the same time opens the drip-passage at 36, so as to allow the liquid which is under the piston 19 to escape and the piston to descend under the load of 120 weight 141 on lever 14, thus causing valve 5 to close. Decrease of pressure beneath diaphragm 50 will cause a lowering of valve-stem 33, so as to open up the passage-ways 125 leading through valve 28 to the under side of piston 19 and at the same time close the drip-passage 36, permitting the liquid-pressure to act beneath piston 19 to raise the same and 130 open the valve 5.

The attachment of the sediment-chamber to the body or casing of the valve 5 and of the pressure-measuring and valve-operating mechanism to the said sediment-chamber secures a very compact and convenient arrangement of the various parts. It enables all of the latter to be supported by the pipe to which the said valve is applied and dispenses with the necessity for providing separate supports for the pressure-measuring devices and valve-operating devices, as heretofore. The pressure-measuring devices are removed from close proximity to the valve 5 and the pipe to which the latter is applied, so that the diaphragm 50 is not exposed to the danger of being injured by the heat from the steam passing through the said pipe and valve. The attachment of the pressure-measuring devices to the sediment-chamber insures the cooling of the former, so as to protect the said diaphragm, the same result being due in part to the mounting of the valve-operating devices upon the base or support B, within which the said diaphragm is located.

In the present embodiment of my invention the pressure-measuring devices comprise, essentially, the diaphragm 50 and the lever D, and the valve-operating devices comprise, essentially, the piston 19, the described connections from the said piston to the valve 5, and the described means of effectuating the movements of the piston under the control of lever D of the pressure-measuring devices; but I wish it to be understood that I do not restrict myself to any particular construction of the valve at 5, of the pressure-measuring devices, of the operating connections of the movable part of the said valve at 5, or of the controlling-valve which is in connection with the pressure-measuring devices. These are not of the gist of my invention and may be of any suitable or approved construction.

What I claim is—

1. The improved pressure-reducing mechanism comprising the steam-valve as at 5, the sediment-chamber attached to the body or casing of the said valve and receiving water

under pressure, the pressure-measuring devices mounted upon the said sediment-chamber, and the valve-operating devices in operative connection with the pressure-measuring devices, mounted upon the casing of the said pressure-measuring devices, and adapted to receive the water from the said sediment-chamber, all substantially as and for the purposes set forth.

2. The combination with the piston having a longitudinally-extending cam, a movable fulcrum-piece engaged by the said cam, the floating lever connected with the said fulcrum-piece, the valve having the valve-stem operatively connected with the said floating lever, and the pressure-measuring devices in operative connection with the said floating lever, substantially as described.

3. The combination with the valve as at 5, of the actuating-piston connected operatively with the said valve and having a longitudinally-extending cam, a movable fulcrum-piece engaged by the said cam, the floating lever connected with the said fulcrum-piece, the valve having the valve-stem operatively connected with the said floating lever, and the pressure-measuring devices in operative connection with the said floating lever, substantially as described.

4. The combination with the valve at 5, of the actuating-piston having a piston-rod which is connected operatively with the said valve, the said piston-rod having the cam extending longitudinally thereof, the fulcrum-slide in engagement with the said cam, the floating lever pivotally connected with the said fulcrum-slide, the valve having the valve-stem operatively connected with the said floating lever, and the pressure-measuring devices in operative connection with the said floating lever, substantially as described.

In testimony whereof I affix my signature in presence of two witnesses.

WILLIAM B. MASON.
